DESIGN FOR A FISHING FLOAT

Gerald M. Marsh, Liberty Mo.

Application July 12, 1945, Serial No. 120,657

Term of patent 14 years

(Cl. D31—4)

To all whom it may concern:

Be it known that I, Gerald M. Marsh, a citizen of the United States, residing at Liberty, in the county of Clay and State of Missouri, have invented a new, original, and ornamental Design for a Fishing Float, of which the following is a specification, reference being had to the accompanying drawing, forming a part thereof.

Fig. 1 is a front elevational view of the fishing float, showing my new design.

Fig. 2 is a side elevational view thereof.

Fig. 3 is a top plan view thereof; and

Fig. 4 is an inverted plan view thereof.

I claim:

The ornamental design for a fishing float, as shown.

GERALD M. MARSH.
